UNITED STATES PATENT OFFICE.

JOSEPH PIERCE, OF PHILADELPHIA, PENNSYLVANIA, ASSIGNOR TO THE AMERICAN CYCLE CAR COMPANY, OF PHILADELPHIA, PENNSYLVANIA, A CORPORATION OF DELAWARE.

INTERNAL-COMBUSTION ENGINE.

1,162,187.

Specification of Letters Patent. Patented Nov. 30, 1915.

Application filed November 6, 1913. Serial No. 799,416.

To all whom it may concern:

Be it known that I, JOSEPH PIERCE, a citizen of the United States, residing at Philadelphia, county of Philadelphia, and State of Pennsylvania, have invented a new and useful Improvement in Internal-Combustion Engines, of which the following is a full, clear, and exact description, reference being had to the accompanying drawings, which form a part of this specification.

The object of my invention is to provide a four cycle internal combustion engine of superior efficiency, economy, simplicity and inexpensiveness.

15 The invention consists of an engine of this type having certain novel means, adapted to the known construction of valve sleeve operable within the engine casing or cylinder, whereby the sleeve is given certain 20 movements and is caused, by such movements, together with the provision of peculiar-shaped ports in the sleeve and casing, to regulate the inlet and exhaust.

A preferred embodiment of the invention 25 is shown in the accompanying drawings, in which—

Figure 1 is a vertical sectional view of an internal combustion engine embodying my invention. Fig. 2 is a vertical section taken 30 on the line 2—2 of Fig. 1. Fig. 3 is an elevation of the inlet side of the cylinder casing. Fig. 4 is a cross section on the line 4—4 of Fig. 3 and Figs. 5, 6, 7 and 8 are diagrammatic views showing the corresponding positions of piston and valve and 35 inlet and exhaust ports at several typical positions in the cycle of operation.

While the invention is shown as embodied 40 in a single cylinder, as many cylinders may be employed, in automobile or other work, as may be found most desirable to meet particular conditions.

The casing of the engine comprises the outer cylinder *a* and the inner cylinder *b*, 45 the two cylinders being spaced apart to accommodate the sleeve *e*, which, as herein-after more fully described, is provided with inlet and exhaust ports and is actuated from the crank shaft in such manner as to 50 properly register with inlet and exhaust ports in the engine and thus control the admission and exhaust of the motive fluid. The upper end of the inner cylinder *b* has 55 formed integral with it the head *c* provided with an annular flange *d* abutting against

the upper end of the outer cylinder *a* and closing the upper end of the annular chamber containing the sleeve *e*.

Within the inner cylinder *b* reciprocates the piston *f* actuated from the crank shaft *g*. The lower end of the inner cylinder has an outwardly extending annular flange *i* spacing the piston chamber from the sleeve chamber. The outer cylinder *a* extends down below the flange *i* and carries the 65 bearings for the crank-shaft and incloses the crank *h*.

At one side of the engine the wall of the outer cylinder *a* is enlarged to form a chamber *m* and carries a bearing for the sleeve-operating shaft *n*. This shaft *n* is driven from the crank shaft *g* by means of the gears *j*, *k* and *l*, of such relative sizes as to impart to the shaft *n* one rotation for each two rotations of the crank shaft. Within the chamber *m* the shaft *n* carries a crank *o* whose pin *p* is slidable within a block *q* carrying trunnions *r* turnable in ears *s* on the sleeve *e*. This connection imparts to the sleeve *e* a combined longitudinal-reciprocatory and axial-turning movement. It will be readily understood that this movement is such that the pin *p* has a truly circular motion, as shown at *x*; but owing to the cylindrical shape of the sleeve, any given point thereon describes a path which, relatively to its own developed surface, is somewhat elliptical. While this method of reciprocating the sleeve *e* is simple and works with the utmost smoothness and maintains 80 the oil between casing and sleeve well distributed, certain difficulties arise in so shaping the ports in the sleeve and in the casing that they will properly register or communicate to effect the opening and closing of the inlet and exhaust at the proper times and to the desired extent. I have overcome 85 these difficulties by providing L-shaped ports both in the casing and in the sleeve and in arranging each pair of registering ports in such manner that the port in the casing is inverted, measuring in two directions perpendicular to each other, with respect to the port in the sleeve. These ports 90 will now be more particularly described.

The outer and inner cylinders are each provided with two inlet ports *t*, the ports of each cylinder registering with the ports of the other cylinder. Each cylinder is also provided with three exhaust ports *v* regis-

tering with similar ports in the other cylinder. The sleeve is provided with two inlet ports u adapted to move into and out of registry with the casing inlet ports t and with three exhaust ports w adapted to move into and out of registry with the casing exhaust ports v .

As will be seen by an inspection of Figs. 5-8, each casing port is inverted, measuring from both a vertical and a horizontal line, relatively to the corresponding sleeve port. That is, each casing port has one arm of the L extending downward and the other arm to the left, while each sleeve port has one arm 15 of the L extending upward and the other to the right. So shaped, corresponding casing and sleeve ports cannot register throughout their areas but register throughout the greater proportion of their areas and are 20 adapted to open and close quickly, to maintain communication for the proper time and to properly vary the open area during the movement between opening and closing.

The operation of the engine may be 25 readily understood from the foregoing description in connection with the diagrammatic views of Figs. 5, 6, 7 and 8, which illustrate four typical or critical points in the cycle of the engine. In Fig. 5 the piston 30 has reached the upper limit of its stroke and the charge has been compressed. About in this position the charge is fired. The sleeve e is in such position that both supply and exhaust are closed. As the piston moves 35 down, the sleeve exhaust ports w approach the casing exhaust ports v until, when the piston has moved some distance beyond its median position toward lower dead center, the exhaust ports v and w just begin to inter- 40 communicate, as shown in Fig. 6. During the completion of the downward movement of the piston and during its upward movement, the exhaust ports v and w remain in communication until the piston has about

completed its upward stroke, at which time 45 the sleeve exhaust ports w move beyond the casing exhaust ports v and the exhaust is cut off, as shown in Fig. 7. Immediately thereafter, as shown in Fig. 7, the sleeve inlet ports u move into position to communicate 50 with the casing inlet ports t and remain in intercommunicating position during the next downward or suction stroke of the piston and until the crank shaft has passed some distance beyond lower dead center, as 55 shown in Fig. 8. At this time the sleeve inlet ports u pass beyond the casing inlet ports t , and during the remaining part of the upward or compression stroke of the piston, the position of the sleeve is such as to 60 maintain closed both the supply and exhaust, as shown in Fig. 5.

Having now fully described my invention, what I claim and desire to protect by Letters Patent is:

65

In an internal combustion engine, the combination of a cylindrical valve sleeve, a casing composed of an inner cylinder and an outer cylinder affording an inclosed annular chamber between them for the reception of 70 the valve sleeve, a piston within the inner cylinder, a crank-shaft connected with the piston, mechanism between the crank shaft and valve sleeve, part of which mechanism extends into said inclosed chamber, adapted 75 to impart to the valve sleeve a combined longitudinally reciprocating and axially-turning movement, there being registering inlet ports and registering exhaust ports in both cylinders and inlet and exhaust ports in the 80 valve sleeve.

In testimony of which invention, I have hereunto set my hand, at Philadelphia, on this 5th day of November, 1913.

JOSEPH PIERCE.
